TOOTH PASTE DISPENSER

John L. Booth, West Palm Beach, Fla., assignor
to Jay G. Glynn, Coral Gables, Fla.

Application March 23, 1949, Serial No. 83,049

4 Claims. (Cl. 222—96)

1

This invention relates to a tooth paste dispenser and, more especially, to improvements in a device for the extrusion of paste from a collapsible tube of conventional type.

The dispensing device to which the invention may have particular application is of the class in which the tube is disposed in an inverted position, having a bottom outlet, and the paste is ejected therefrom in predetermined quantities in a step-by-step application of compression thereto.

Any object of the invention is to provide a tooth paste dispenser having a positive and sanitary closure means effective to seal the tube outlet upon the discharge therefrom of a predetermined quantity of the paste.

Another object is to provide a dispensing device of the character described which will be simple and efficient in use.

A further object is to provide a tooth paste dispenser which may be readily and economically manufactured.

Other advantages of the invention will be discernible from the description thereof hereinafter set forth.

According to the invention, the tooth paste dispenser comprises a case adapted to receive a collapsible tooth paste tube arranged therein in inverted position and having a bottom outlet, normally sealed valve means communicating with the outlet tube compression means operable to extrude the paste therethrough, a trigger operable to actuate the compression means, valve sealing means detachably connected to the trigger and operable thereby to unseal the valve in co-operation with operation of the compression means, means actuated by the tube compression means to detach the valve sealing means from the trigger to re-seal the valve upon the extrusion of a predetermined quantity of paste, the case has a brush passage normally closed by a plunger gate adapted to engage the trigger to actuate the extrusion and valve sealing means upon the inward thrust of a tooth brush impelled against the plunger gate in the introduction of the brush into paste receiving relation with the tube outlet.

The invention is exemplified in a tooth paste dispenser shown in the accompanying drawings in which the views are as follows: like reference numerals designating identical parts throughout the several views:

Fig. 1, a longitudinal sectional elevation through the case;

Fig. 2, a portion of the view shown in Fig. 1;

2

Fig. 3, an interior elevation of the cover; Fig. 4, a perspective of the dispenser case; Fig. 5, a perspective of the roller and; Fig. 6, a fragmentary sectional view therethrough;

Fig. 7, a partial interior elevation of the back of the case, taken on line 7—7, Fig. 8;

Fig. 8, a sectional plan on line 8—8, Fig. 7;

Fig. 9, an isometric view of the valve sealing means.

The dispenser has a housing or case consisting of a back or bracket portion 1, and a complementary front cover portion 2. The back and cover portions have the usual wall, bottom and top members, and are designed to fit together into a unitary compartment adapted to accommodate the dispenser mechanisms. The back, or bracket, portion 1 may be fitted with any suitable fastenings (not shown) for attachment to a wall or other supporting structure.

Arranged within the cover portion 2 and occupying an inverted position thereagainst, is a conventional collapsible tooth paste tube 3, having the usual threaded neck whereby it is received into a nipple or nozzle 4 fitted thereover. The nozzle 4 may be fabricated from latex or a like substance having suitable characteristics of resiliency and yieldability.

Adjacent the bottom ends thereof, the back and cover portions have fitted therein a seat block consisting of two complementary horizontal block members, one of which is shown at 5, seated in the back portion, and the other, shown at 5a, is seated within the cover portion, these two block members being adapted for assembly into a supporting block for the tube 3, and assisted in alignment by a tongue 5b, formed in the back portion block (Fig. 7), and a groove 5c, cut into the cover portion block (Fig. 3). Each block member 5 and 5a has a semi-circular recess slotted in the edge thereof as at 6 (Fig. 8), to form a socket, when the two blocks are assembled, for reception of the nozzle 4.

Extending forwardly from the inner face of the back portion, is a central rib 7 (Fig. 1), having a forwardly and downwardly inclined front edge on which is supported a toothed rack 8 having limited reciprocal movement relative to the rib 7.

The rack 8 is received at its upper end in a recess 9 formed in the top of the back portion 1, and at its lower end is received within a well formed in a trunnion block 10 carried by the block member 5. The rack is held in normally raised position by a spring 11, having its upper

end secured to the rib 7 and its lower end fastened to a claw member 12 which is formed at the lower extremity of the rack.

The trunnion block 10 carries a transverse pivot pin 13 on which is mounted a trigger 14, having a forwardly disposed cam 15 adapted for engagement with the adjacent arcuate face of the claw member 12 (Fig. 1). Abutting the nozzle 4 and in normal compressing relation therewith, is a convex-nosed snubber 16, having a pair of rearwardly extending bottom runners 16a (Fig. 9), whereby the snubber is mounted for reciprocal movement relative to the nozzle 4, the seat block member 5 being suitably recessed to accommodate the snubber structure, as will be understood. At its upper end, the snubber is detachably connected to the trigger by a rearward extension 17 forming a spring pawl member terminating in a hook 17a which normally engages a notch 18 formed in the trigger. Thus, the trigger is pivotably rearwardly to carry therewith the snubber 16 against the influence of a spring 19, secured at its front end to the snubber and at its rearmost end to a pin 20 suitably anchored to the block member 5.

The cover portion 2 is apertured, as at 21, to receive a gate 22 having a resilient connection inwardly thereof with a follower 23 from which it is normally spaced by a spring 24, the ends of which are secured to the adjacent faces of the gate and follower for a purpose to be presently explained. The gate and follower have reciprocal slideable movement in a bridge or trackway 25 extending rearwardly of the cover portion and carried thereby.

Meshing with the rack 8 is a gear ring 26 encircling a roller 27 about the mid-portion thereof (Figs. 1 and 6). The roller comprises a first cylinder 28 terminating at its outer end in a pin 29 and extended at its inner end in a cylindrical shaft 30, the outer end of which, in turn, terminates in a square, tapered shaft 31 having a pin 32 formed thereon. A second cylinder 33, suitably recessed axially thereof to accommodate the shafts 30 and 31, is alined with the first cylinder 28 to form the roller, the gear ring 26 being passed theraround so as to rotate independently of the roller assembly. Coiled about the shaft 30 is a helical spring 34 having one end secured to the gear ring and the opposite end fastened to the shaft 30. Thus, when the gear ring is turned in one direction the spring 34 tightens about the shaft 30 to rotate the roller assembly therewith but when turned in the opposite direction the gear ring has limited independent rotation relative to the roller assembly, for a purpose to be presently described.

The roller is adapted to travel in downward movement relative to the tube 3, the pins 29 and 32 engaging a groove 35 formed in each side of the cover portion. These grooves terminate at their upper and lower ends in a rearwardly extending elbow portions 36 whereby to permit the removal of the roller from the cover portion 2.

In practice, the dispenser is loaded by disassembling the cover portion from the back portion, the two portions of the case being normally fastened by any suitable latching device well known in the art, and arranging the paste tube against the inner face of the cover portion. The roller is adjusted against the upper flat portion of the tube, the neck of which is fitted into the nozzle 4 and the nozzle seated in the socket 6.

The cover portion is then reassembled with the back portion, bringing the nozzle 4 into

sealing relation with the snubber 16 and the follower 23 into engageable alignment with the trigger 14, as illustrated in Fig. 1.

The tooth brush 37 is impelled against the gate 22 which is plunged inwardly thereby, in turn impelling the follower 23 into engagement with the trigger which is thus pivoted to the position occupied thereby in Fig. 2. The cam 15, engaging the claw member 12, depresses the rack to impart rotation to the roller in a downward direction, thereby extruding the contents of the tube by virtue of the compression exerted thereon by the roller. The pivotal movement of the trigger carries the snubber rearwardly to unseal the nozzle 4, and the claw member being depressed against the pawl member 17 in the descent of the rack 8, the pawl member is released from its engagement with the trigger and the snubber returned under the influence of the spring associated therewith to sealing relation with the nozzle 4. It will be observed that the release of the snubber to permit its return to sealing position takes place at or near the extreme rearward position of the trigger, so that the closure of the nozzle is effected while the brush is still in paste receiving position under the nozzle 4, thereby eliminating the necessity of withdrawing the brush from the device to cut off the extrusion of paste.

When the brush is withdrawn, the gate and follower are retracted under the influence of the trigger returning to its original position by virtue of the retraction, upwardly, of the rack 8, under the influence of the spring 11. In this movement the rack is retained in mesh with the gear ring 26 which, by reason of the roller construction above set forth, is free to rotate with the upwardly moving rack without rotating the roller therewith.

To assist in braking the roller against reverse rotation upon the upward retractive travel of the rack 8, I may provide the roller with the mechanism shown in Fig. 5, wherein the pins are fitted with a shoe 38 at each end of the roller. These shoes carry a downwardly inclined blade 39 having a scalloped edge adapted to engage the peripheral surface of the roller to resist its rotation thereagainst. The shoes may be slideably supported in travel upon a pair of complementary flanges 40 formed against the inner faces of the sides of the cover portion. The roller may be covered with a peripheral working surface 41, of rubber or like resilient material (Fig. 6). A pair of toothed guide racks 42 may be formed against the inner face of the cover portion and spaced along the marginal edges thereof, for frictional engagement by the rubber periphery of the roller.

It is to be understood that while the foregoing exemplification of my invention has been directed to a dispensing device for tooth paste contained in a collapsible tube, the invention has application to the dispensing of the contents of any tube of the collapsible type where a brush is impellable against a gate as described herein. Certain modifications to the shape and conformation of the gate and brush passage leading thereto are feasible within the scope of the invention.

It will thus be seen that the invention provides a dispenser of novel construction and operation, meeting the objects hereinbefore set forth.

Of course, the invention is susceptible of various modifications without departing from the scope thereof as hereinafter claimed.

Having thus described the invention and the mode of its practice, what I claim as new and desire to secure by Letters Patent is:

1. In a paste dispenser, in combination with a case adapted to receive a collapsible, paste-containing tube having a bottom outlet, a roller journaled in said case and engageable with said tube for the extrusion of paste therefrom, a gear encircling said roller, a rack mounted for reciprocation in said case and engageable with said gear, a resilient nozzle communicating with said outlet and a snubber mounted for reciprocation in said case and normally engageable with said nozzle in sealing relation therewith, a trigger operatively connected with said rack and releasably engaged with said snubber and operable to simultaneously actuate said rack and withdraw said snubber out of nozzle sealing relation, means carried by said rack to disengage said trigger from said snubber to permit the retraction thereof into nozzle sealing relation upon the extrusion of a predetermined quantity of paste.

2. In a paste dispenser, in combination with a case adapted to receive a collapsible, paste-containing tube having a bottom outlet, a roller journaled in said case and engageable with said tube for the extrusion of paste therefrom, a gear encircling said roller, a rack mounted for reciprocation in said case and engageable with said gear, a resilient nozzle communicating with said outlet and a snubber mounted for reciprocation in said case and normally engageable with said nozzle to constrict the passage therethrough, a trigger operatively connected with said rack and releasably engageable with said snubber, a brush-impelled plunger gate arranged in said case and engageable with said trigger for the actuation thereof to simultaneously actuate said rack and withdraw said snubber out of nozzle sealing relation to effect the extrusion of a predetermined quantity of paste upon said brush, means carried by said rack to disengage said trigger from said snubber to permit the retraction thereof into nozzle sealing relation in advance of the withdrawal of said brush from said case.

3. In a paste dispenser, in combination with a case adapted to receive a collapsible, paste-containing tube having a bottom outlet, a valve communicating with said outlet, a trigger, means operable by said trigger to compress said tube for the extrusion of paste therefrom, means operatively connected with said valve normally effecting the sealing thereof and releasably engaged with said trigger and operable thereby to effect unsealing of said valve simultaneously with the operation of said extrusion means, said valve sealing means being disengageable from said trigger to re-seal said valve by the operation of said extrusion means upon the extrusion of a predetermined quantity of paste from said tube.
4. In a paste dispenser, in combination with a case having a brush passage and a plunger gate normally closing said passage, said case being adapted to receive a collapsible, paste-containing tube having a bottom outlet, a valve communicating with said outlet, a trigger engageable by said gate upon the inward thrust of a brush impelled thereagainst, means operable by said trigger to compress said tube for the extrusion of paste therefrom, means operatively connected with said valve to normally effect the sealing thereof and having disengageable connection with said trigger and operable thereby in co-operation with said tube compression means, said valve sealing means being disengageable from said trigger by operation of said tube compression means to re-seal said valve in the course of said inward thrust and upon the extrusion of a predetermined quantity of paste from said tube.
